(57) **CLAIM**

The ornamental design for a workstation, as shown and described.

DESCRIPTION

FIG. 1 is a perspective view of a workstation according to a first embodiment of our new design, shown in a first configuration of use. A second embodiment of the design in a first configuration consisting of a mirror-image thereof; FIG. 2 is a front elevation view thereof; FIG. 3 is a back elevation view thereof; FIG. 4 is a right side elevation view thereof; FIG. 5 is a left side elevation view thereof; FIG. 6 is a top plan view thereof; FIG. 7 is a bottom plan view thereof
FIG. 8 is a perspective view of the workstation according to the first embodiment of our new design, shown in a second configuration of use. The second embodiment of the design in a second configuration consisting of a mirror-image thereof; FIG. 9 is a front elevation view thereof; FIG. 10 is a back elevation view thereof; FIG. 11 is a right side elevation view thereof; FIG. 12 is a left side elevation view thereof; FIG. 13 is a top plan view thereof; and, FIG. 14 is a bottom plan view thereof.

The portions of the article shown in broken line form no part of the claimed design.

The dot-dash broken lines represent the boundaries of the claim and form no part thereof.

1 Claim, 12 Drawing Sheets
